HUGO E. GRIESHABER, OF NEW LONDON, CONNECTICUT, ASSIGNOR TO ELECTRIC BOAT COMPANY, OF GROTON, CONNECTICUT, A CORPORATION OF NEW JERSEY

RESCUE TANK

Application filed September 4, 1928. Serial No. 303,707.

This invention relates to rescue devices for use with submarine boats, and more particularly to tanks or cars for removing the men from a disabled submarine, and to gear and guiding means for conveying the tank to and seating it upon the escape hatch trunk.

At depths of approximately one hundred feet, it is practicable for the men to swim to the surface to be rescued. In my co-pending application for escape hatch for submarines, Serial No. 275,730, filed May 7, 1928, I have disclosed a hatch construction, and means for opening the outer hatch cover from within the hull, permitting men enclosed in a submarine to escape safely through the hatch.

If the disabled boat be at a depth in excess of approximately one hundred feet, it is necessary to employ rescue cars or tanks to effect the rescue of the entrapped men. Such a car, capable of removing a number of men at one time, is disclosed in my co-pending application Serial No. 266,541, filed April 2, 1928, for rescue buoy. The car of my application identified requires the use of guide lines and divers in properly positioning it upon the hatch. In rescuing men from a disabled submarine boat, particularly one which has been disabled by collision, time is an essential consideration. A material saving of time can be effected by eliminating the necessity of using divers or guide lines in positioning the rescue tank upon the hatch trunk. My instant invention is, primarily, directed to this.

One of the main objects of my invention is to provide a rescue tank having an associated guiding structure so arranged as to guide the tank onto the hatch trunk of the submarine in proper relation thereto. A further object is to provide means operable from within the boat for drawing the tank to the hatch trunk and causing the guiding structure to enter the same. Another object is to provide a cable for attachment to the tank and winding means for the cable, carried by the boat and so arranged as to leave the hatch trunk clear and unobstructed for use when the hatch covers are open, as when the boat is on the surface. Further objects and

advantages of my invention will appear from the detail description.

In the drawings:

Fig. 1 is a sectional view through a tank and a hatch trunk provided with cable winding means, in accordance with my invention, parts being shown in elevation and broken away, and the tank being broken away;

Fig. 2 is a sectional view through a modified form of tank and the outer portion of a hatch trunk, in accordance with my invention, parts being shown in elevation; and

Fig. 3 is a section through the tip member of the guiding structure, and associated parts, parts being shown in elevation.

In Fig. 1 I have illustrated a tank 1 comprising a top section 2, a mid-section 3 and a bottom section 4, suitably secured together, as by welding. This tank is preferably of circular cross-section and is capable of withstanding the high pressures which obtain at great depths. Section 4 is provided with an inwardly projecting flange 5 defining a hatch opening 6, and with an outwardly extending annular shoulder 7 having a recess in which is mounted a gasket 8. Flange 5 is provided with a recess in which is mounted a gasket 9. This gasket cooperates with a cover 10 to form a tight closure about opening 6. The cover is secured closed by dogs 11, of known type, which can be operated from either side of the cover for releasing or securing the same, in a manner well understood in the art.

Bottom section 4 of the tank is further provided with a downwardly projecting annular rib 11', the outer face 12 of which is inclined from shoulder 7 downwardly and inwardly of the car. Surface 12 of rib 11 forms a seat for the base of a frusto-conical guide member 13. This member is secured to a ring 14 secured to the outer ends of a pair of arms 15 joined by a collar 16 slidable on a rod 17. The upper end of this rod screws into a boss 18 integral with cover 10. A handle 19 is feathered on the rod to facilitate screwing it into and out of the boss. A nut 20 screws onto rod 17 and is turned up tight against handle 19, after the rod has

been screwed into boss 18, for locking the rod in position.

A tip structure is mounted on the lower end of rod 17 and acts to secure a cable thereto and to hold the guide member seated upon the rib 11. This structure comprises an upper frusto-conical member 21 and a lower socket member 22, these two members being connected for relative turning movement by a channel ring 23 the flanges of which engage into grooves 24 and 25 of members 21 and 22, respectively.

Member 21 screws upon the lower end of rod 17. To facilitate screwing the member onto and off of the rod, handles 26 are pivotally secured, at 27, in member 21. These handles, when not in use, are disposed in openings 28 in member 21. A cable 29 is passed into socket member 22 and has its end portion spread and shaped, in a known manner, to form a head 30 which fits into the socket member.

When member 21 is secured onto rod 17 it contacts with the lower end of member 13 and holds the latter tightly upon its seat 12. The members 13, 21 and 22 constitute a guiding structure of conical shape extending downwardly from shoulder 7. This structure is free of all projections and is highly effective in guiding the tank into, and positioning it upon, the hatch trunk.

The tank, in conjunction with the guiding and centering means, is used with a hatch trunk 31 which extends through hull 32 of a submarine boat of known construction. The upper end of this trunk is disposed adjacent deck 33 of the super-structure. Trunk 31 is of what may be considered standard or conventional type and is provided with a removable cover or closure at each end.

The trunk 31 is provided with a lower section 34 secured to the body of the trunk in a suitable manner, as by the angle ring 35, and forming a continuation thereof. This lower section carries the lower cover 36, hinged thereon in a known manner, for closing the inner end of the trunk. In practice, this cover is secured closed by suitable dogs, in a known manner.

A drum casing or housing 37 is suitably mounted on the upper or outer face of cover 36. Housing 37 is provided with an upwardly directed and upwardly flaring throat member 38 through which cable 29 passes to a drum 39 rotatably mounted in the housing, the cable being windable onto and off of this drum, and the throat member being disposed centrally of trunk 31 when cover 36 is closed. A bevel gear 40 is secured to one end of the drum and meshes with a pinion 41 secured on the upper end of a stub shaft 42 rotatably mounted in the base of housing 37.

A spur gear 43 is secured on stub shaft 41 and meshes with a spur pinion 44 secured on

a shaft 45 rotatably mounted through bosses 46 and 47 of the housing and cover, respectively.

Cover 36 is provided, on its under face, with suitable lugs 48 to which is secured a gear housing 49 which is closed and has an accurate fit against the under face of the cover about shaft 45, a gasket being interposed between the gear housing and the cover to provide a water tight and pressure resistant closure about the shaft at this point. Shaft 47 extends into housing 49 and into a boss 50 at the under face of the housing, the boss being closed by a cap 51 and an associated gasket to provide a water tight closure. A bevel gear 52 is secured on shaft 47 and meshes with bevel pinions 53 secured on the inner ends of shafts 54 rotatably mounted through bosses 55 of the gear housing, and collars 56 at the outer ends of arms 57 projecting from the housing. Cranks 58 are secured on the outer ends of shafts 54. Each of these cranks is provided with a handle 59 of a length to be readily grasped by two men. Preferably, though not necessarily, a stuffing box 60 is provided about each shaft 54 to prevent escape of water from the gear housing 49.

Normally, when the boat is submerged, the inner and outer covers of hatch trunk 31 are closed. In the event of the boat being disabled, through collision or otherwise, the inner cover 36 is opened and the end of the cable 29 is attached to a suitable float or buoy which is inserted into the trunk 31, and cover 36 is then again secured closed.

This float may be of any suitable type and, preferably, is such that it may be used for storing goods in upon the boat. This is of advantage as space is at a premium on a submarine boat.

After the float has been placed in the hatch trunk and the inner cover closed, water is admitted from the exterior of the hull into the trunk to equalize the pressures on the inner and outer surfaces of the outer hatch cover. This may be accomplished by any suitable arrangement of valves, such as that disclosed in the co-pending application of Lawrence Y. Spear for rescue car, filed February 20, 1928, Serial No. 255,682. The outer hatch cover is then opened from within the boat, by any suitable means such as that disclosed in my co-pending application for escape hatch for submarines, filed May 7, 1928, Serial No. 275,730. The cable is then unwound from the drum sufficiently to permit the float to rise to and float upon the surface.

The tank, including the member 13, cover 10 and rod 17, is carried by the rescue ship, and the members 21 and 22 are preferably permanently attached to the cable 29, though these members may also be carried by the rescue ship and attached to the cable on board the rescue ship, if this seems desir-

able. If the members 21 and 22 remain permanently attached to the cable, the container on board the submarine boat, which is to be used as a float, may be provided with a suitable screw stud by means of which member 21 can be quickly secured to the float.

The rescue ship can quickly locate the float on the surface, which is picked up, and the cable is then secured to rod 17, by means of member 22, in the manner previously described, this rod being, of course, first secured to cover 10 which has been secured to the car in closed position. When the car has been properly secured to the cable, the men on the submarine are apprised of this fact in a suitable manner, and they then wind cable 29 back onto the drum 39 hauling the car down. The car may have either positive or negative buoyancy imparted thereto in any suitable manner, such as that disclosed in my copending application for rescue buoy above identified. If the car has positive buoyancy, the cable 29 serves to haul it down, and if it has negative buoyancy it is lowered from the rescue ship by a suitable cable 62 secured through eye 61 at the top of the tank.

As the tank approaches the hatch trunk 31 the conical guiding structure enters the trunk and guides the car into proper relation thereto so that gasket 8 seats upon the outer end of the trunk. Cable 29 is then wound tightly onto the drum to hold the car in position and the water is drained from the trunk in a suitable manner. The preponderance in pressure of the water on the car 1 now serves to hold the car tightly seated upon the trunk 31. The inner cover 36 is now opened and the member 22 is detached from rod 17. Member 13 is then removed and rod 17 is removed from cover 10. Cover 10 is then opened and the men enter the car, closing and securing the cover. The car is then raised to the surface by the rescue ship, by means of cable 62, and the men are removed.

In the event that all of the men in the compartment of the submarine into which the trunk 31 opens, are unable to enter the car, the men remaining in such compartment replace the rod 17 and members 13, 21 and 22, and unwind the cable as the car is raised, the car being returned, as before, to rescue such men remaining in the compartment.

The rescue car 1^a illustrated in Fig. 2 is similar in all respect to that of Fig. 1 except that it is more nearly cylindrical and can accommodate a greater number of men.

The cars have been illustrated more or less diagrammatically. In practice these cars may be equipped with suitable telephone instruments and cables for communicating with the rescue ship, as well as air hose, means for regulating the buoyancy of the tanks, and other equipment. The tanks may, however, be used without such equipment.

It is to be particularly noted that the cable

drum and associated parts are mounted upon the inner cover of the hatch trunk. When this cover is in open position, the hatch trunk is clear and unobstructed and is used to give ingress and egress to and from the hull in the usual manner. My invention is thus well adapted for use with submarine boats of accepted design as it can be applied to hatch trunks of present construction without interfering with the normal use of such trunks, does not necessitate the provision of additional hatch trunks or similar structures, and does not occupy valuable space which could be put to other uses.

While I have illustrated hand operated means for turning the cable drum, I do not limit myself to such means. I contemplate the provision of suitable power means, such as a compressed air motor, mounted upon the inner hatch cover 36.

I also contemplate the use of a jointed rod permanently secured to cover 10 of the tank, instead of the rod 17, if desired, such jointed rod permitting opening of cover 10 into tank 31 after removal of member 13. Any suitable means may be employed for attaching the cable to the tank, and for holding the centering and guiding structure assembled and I do not, therefore, limit myself to the particular construction illustrated.

What I claim is:—

1. In combination with a submarine boat, a hatch trunk extending through the hull of the boat, removable covers for the ends of the trunk, cable winding means operable from within the hull, a cable windable onto and off of said means through the outer end of the trunk when the outer cover is removed, a rescue car having a hatch opening at its lower end and a removable cover therefor, a guide member extending from the lower end of the car and adapted to enter the outer end of the trunk and center the car relative thereto, and means for detachably securing the cable to the car and for removably holding the guide member in operative relation to the car.

2. In combination, a rescue car having a hatch opening at its lower end, a removable cover for said opening, a removable tapered guiding member having its base abutting the car and extending about the cover, and releasable means for attaching a cable to the lower end of the car and for holding the guiding member against movement away from the car.

3. In combination, a rescue car having a hatch opening at its lower end, a cover for said opening, releasable means for securing the cover to the car in closed position, the car having an annulus adapted for seating upon a hatch trunk and being provided with a downwardly and inwardly inclined surface disposed inwardly of the annulus, a rod secured to and depending from the cover, a downwardly tapering guide member having

its base seating upon said inclined surface, a tip member adapted for securing to a cable, and means for releasably securing the tip member on the lower end of the rod with its upper end abutting the lower end of said guide member.

4. In combination, a rescue car having a hatch opening at its lower end, a removable cover for said opening, a downwardly tapering removable guide structure abutting the car about said opening, means for centering said structure relative to the cover, the car having a shoulder projecting outwardly beyond said structure and adapted to seat upon the outer end of a hatch trunk, and means for attaching a cable to the guide structure at the lower end thereof.

5. In combination, a rescue car having a hatch opening at its lower end, a removable cover for said opening, the car having an annular outwardly projecting shoulder adjacent said opening and adapted for seating upon the outer end of a hatch trunk, and a downwardly tapering guide member extending from the lower end of the car with its base inside of and concentric with said shoulder.

6. In combination, a rescue car having a hatch opening at its lower end, a removable cover for said opening, said car having an outwardly projecting annular shoulder beyond the opening adapted for seating upon the outer end of a hatch trunk, the car also having a downwardly and inwardly inclined surface extending from the shoulder, and a downwardly tapering guide structure extending from said surface.

7. In combination in a submarine boat, an access hatch trunk extending through the hull and having its lower end adjacent the top of the hull, removable covers for the ends of the trunk, cable winding means carried by the inner cover and disposed within the trunk when said inner cover is closed, said means being movable with the inner cover clear of the trunk, the interior of the trunk being unobstructed when the inner cover is open and said trunk providing free ingress to and egress from the hull when the boat is on the surface, and means operable from within the hull for operating said winding means.

8. In combination in a submarine boat, an access hatch trunk extending through and projecting outwardly beyond the hull, removable covers for the ends of the trunk, cable winding means carried by the inner cover and disposed within the trunk when said inner cover is closed, said means being movable with the inner cover clear of the trunk, the interior of the trunk being unobstructed when the inner cover is open and the trunk providing free ingress to and egress from the hull when the boat is on the surface, and means operable from within the hull for operating said winding means.

9. In combination in a submarine boat, an access hatch trunk extending through the hull, removable covers for the ends of the trunk, cable winding means carried by the inner cover and disposed within the trunk when said inner cover is closed, said means being movable with the inner cover clear of the trunk, the interior of the trunk being unobstructed when the inner cover is open and said trunk providing free ingress to and egress from the hull when the boat is on the surface, and means operable from within the hull for operating said winding means.

10. In combination in a submarine boat, an access hatch trunk extending through and projecting outwardly beyond the hull, the inner end of the trunk being disposed adjacent the top of the hull, removable covers for the ends of the trunk, cable winding means carried by the inner cover and disposed within the trunk when said inner cover is closed, said means being movable with the inner cover clear of the trunk, the interior of the trunk being unobstructed when the inner cover is open and said trunk providing free ingress to and egress from the hull when the boat is on the surface, and means operable from within the hull for operating said winding means.

11. In combination, a rescue car having a hatch opening at its lower end, a removable cover for said opening, a removable tapered guiding member having its base abutting the car and extending about the cover, said member being free of projections, and releasable means for attaching a cable to the lower end of the car and for holding the guiding member against movement away from the car.

12. In combination with a submarine boat, a cylindrical hatch trunk extending through the hull of the boat, removable covers for the ends of the trunk, cable winding means operable from within the hull, a cable windable onto and off of said means through the outer end of the trunk when the outer cover is removed, a rescue car having a hatch opening at its lower end and removable cover therefor, the car having an annulus about said opening and adapted for seating upon the outer end of the trunk, a downwardly tapering guide member adapted to enter the trunk and having its base seating against the car within and concentric to said annulus, said guide member being free from projections, means accessible exteriorly of the car for detachably securing the guide member thereto, and means for detachably securing the cable to the guide member.

In witness whereof, I hereunto subscribe my name.

HUGO E. GRIESHABER.
